CLAIM

The ornamental design for a portion of a display panel or screen with an icon, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first embodiment of a portion of a display panel or screen with an icon showing our new design;

FIG. 2 is a front view of a second embodiment of a portion of a display panel or screen with an icon showing our new design;

FIG. 3 is a front view of a third embodiment of a portion of a display panel or screen with an icon showing our new design; and,

FIG. 4 is a front view of a fourth embodiment of a portion of a display panel or screen with an icon showing our new design.

The evenly-spaced broken lines illustrate unclaimed portions of the design and form no part of the claimed design. The single dot-dash broken lines define boundaries of, and are not included in the claimed design. The double dot-dash broken lines in each figure show a portion of a display panel or screen and define the boundaries thereof, but not included in, the claimed design.
